UNITED STATES PATENT OFFICE.

HENRY D. JAMES, OF EDGEWOOD PARK, PENNSYLVANIA, ASSIGNOR TO WESTINGHOUSE ELECTRIC & MANUFACTURING COMPANY, A CORPORATION OF PENNSYLVANIA.

CONTROL SYSTEM.

1,421,244.

Specification of Letters Patent. Patented June 27, 1922.

Application filed November 4, 1918, Serial No. 260,949. Renewed March 23, 1922. Serial No. 546,183.

To all whom it may concern:

Be it known that I, HENRY D. JAMES, a citizen of the United States, and a resident of Edgewood Park, in the county of Allegheny and State of Pennsylvania, have invented a new and useful Improvement in Control Systems, of which the following is a specification.

My invention relates to reversing systems for electric circuits, especially electric motors, and is particularly adapted for use in connection with motor-control systems of the character set forth in my co-pending application, Serial No. 236,937, filed May 27, 1918, control systems, patented September 27, 1921, No. 1,392,056.

The reversing systems forming the subject-matter of the present application are modifications of those found in my co-pending application, Serial No. 249,344, filed August 10, 1918, patented September 27, 1921, No. 1,392,057, in which the acceleration of the motor is controlled by an energizing coil in parallel circuit with the accelerating resistor through its influence over a relay, preferably of the type illustrated in a co-pending application of De Camp, Serial No. 241,259, filed June 21, 1918, and assigned to the Westinghouse Electric Manufacturing Co. The relay is maintained closed by a holding circuit.

The object of my invention is to provide an improved reversing system of this character.

According to my present invention, I so arrange the control circuits of the motor that it is impossible to start or reverse it, until the main armature of the above-mentioned De Camp relay has first been actuated to release the relay armature. Such a system is more particularly illustrated at Fig. 8 of my above-mentioned application, Serial No. 249,344. In the present system, the circuit of the coil, mentioned above as being in parallel relation to the accelerating resistor, is closed only when the reversing contactors are in their inoperative positions, by switches mechanically connected to them. According to one form of my invention, the main armature of the De Camp relay is initially actuated by this energizing coil and, according to another form of my invention, this armature is actuated by the above-mentioned holding coil.

In the accompanying drawings, Figs. 1,

2 and 3 are respectively a side and an end elevation, and a plan view of a relay of the type illustrated in the aforementioned application of De Camp. Fig. 4 is a diagrammatic view of circuits and apparatus illustrating one form of my invention, and Fig. 5 is a similar diagrammatic view illustrating another form of my invention.

As my invention is of particular value in a system employing the above-referred-to De Camp relay, illustrated in Figs. 1 to 3, it will conduce to clearness to describe this relay first.

An insulating panel 29 carries two brackets 30 and 31 supporting coils 22 and 23 which, when energized by current flowing through them, produce magnetic fields for attracting an armature 32 and any desired number of additional armatures 33, 34 and 35. A compression spring 36 is adjustably mounted upon a non-magnetizable rod 37, slidably mounted in arms 38 and 39, which are rigidly connected to, or constitute integral parts of, the bracket 31. The arm 38 serves also as a pole piece for the armature 32, and the arm 39 as a pole piece for the armatures 33, 34 and 35. A bar 40 is rigidly connected to the rod 37 and normally engages the armatures 33, 34 and 35. The spring 36 thus normally maintains the armatures 33, 34 and 35 in their open positions, with the members 41, which are carried by these armatures, in contact with the pole piece 39. The members 41 are preferably of non-magnetizable material to prevent "freezing".

The armature 32 is provided with ears or lugs 42, which are pivotally mounted upon the bracket 30, and is normally maintained in contact with one end of the rod 37 by a weak spring 43. The bracket 30 supports a non-magnetizable, U-shaped member 44 between the arms of which are pivotally mounted the armatures 33, 34 and 35, which carry, respectively, the movable contact members 45, 46 and 47 of relays 25, 26 and 27. The corresponding stationary contact members 48, 49 and 50 are mounted upon the insulating panel 29.

Springs 51 are attached to longitudinally adjustable members 52 and to the other ends of the members 41. The pole piece 39 is provided with longitudinally adjustable members 53 to regulate air gaps 70 between these members and the corresponding arma-

tures. By means of this adjustment, or by means of the members 52, which control the tension of the springs 51, the action of the magnetic flux produced by the coils 22 and 5 23 may be so regulated that the armatures 33, 34 and 35 will be operated in proper sequence.

The armature 32 is provided with an extension 54, preferably of insulating material, 10 which carries a switch member 55 for co-operating with stationary switch members 57 mounted upon the insulating panel 29. As shown in Fig. 1, the switch members 55 and 57 are open when the armature 32 15 occupies its normal or open position.

The operation may be briefly described as follows. Upon current flowing through the coil 22, a magnetic field is produced which causes the armature 32 to be attracted 20 toward the pole piece 38. The force of the spring 36 is thereupon overcome, and the bar 40 is moved out of engagement with the armatures 33, 34 and 35, the stop members 41 of which are, nevertheless, maintained 25 in engagement with the pole piece 39 until the flux of the magnetic field successively becomes sufficiently low to permit the springs 51 to successively actuate the movable contact members 45, 46 and 47, thereby 30 to close the relays 25, 26 and 27. In the event that the magnetic field becomes too weak to hold the armature 32 in its elevated position, the spring 36, becoming released, will separate the movable from the 35 stationary contact members. Actuation of the armature 32, of course, effects corresponding actuation of the switch member 55.

I shall now describe the invention illustrated in Fig. 4. A motor, the armature 40 of which is shown at 1 and the shunt field-magnet winding at 2, is connected between line conductors 3 and 4, with a regulating resistor 6 normally in series with the armature 1. Although I have here shown, for 45 purposes of illustration, a shunt-wound motor, it will be understood that my invention is equally applicable to a series or compound-wound motor. A plurality of reversing contactors 59, 60, 58 and 61, mention 50 mechanically interlocked in pairs, control the direction of rotation of the motor. A master controller or switch 7 controls the actuation of the reversing contactors through the medium of energizing coils 62 and 63. 55 The movable contact members of contactors 66 and 67 are, respectively, mechanically interlocked with the movable contact members of the reversing contactors for a purpose below described. The movable member 60 of the master controller 7 is designed to bridge contact members 9a, 9b, 16, 17, 18a and 18b, in a certain order, when operated as hereinafter specified. One or more contactors 10, 11 and 12 (three are illustrated) 65 control the shunting of successive portions

13, 14 and 15 of the regulating resistor 6, through the medium of energizing coils 19, 20 and 21. The coil 22 is connected across the terminals of the resistor 6, at 79 and 80, in series with a resistor 86. The energizing 70 of the coil 22 causes the successive closing of the relays 25, 26 and 27, as above described, in accordance with the strength of the current passing through the coil 22. The coil 19 is connected in a circuit leading 75 from the line conductor 3, by a conductor 28, through the contact member 16 or the member 17, according to the position of the controller 7, the coil 19, the relay 25, the point 80 and a line contactor 5, to the line conductor 4. The coils 20 and 21 are similarly connected to the relays 26 and 27 in parallel to the coil 19 and the relay 25. The circuit of the coil 23 is closed at the same time as that of the coil 85 21 by the relay 27. The line contactor 5 is adapted to be actuated by a coil 8, which is controlled by contact members 9b and 18b, according to the "forward" or "reverse" 90 position of the controller 7. I provide for initially energizing the coil 22 by connecting it in circuit with the contact members 66 and 67, and a resistor 24, as described below.

The operation is as follows: When the controller 7 is actuated to the left, a circuit is 95 established from the line conductor 3, by the conductor 28, through the contact members 9b and the coil 8, to the line conductor 4. The contactor 5 is thereupon closed. A second circuit extends from the contact members 9b, through the contactors 67 and 66, the resistor 24, the coil 22, the point 80 and the contactor 5, to the line conductor 4. The coil 22 is thus energized by line voltage to cause the actuation of the armature 32 to the 105 pole piece 38, in opposition to the force of the spring 36, thereby to release the armatures 33, 34 and 35, and to close the contact members 55 and 57 (Fig. 1). A circuit is thereupon established from the line conductor 3, by the conductor 28, through contact members 9a, the actuating coil 63, the contact members 55 and 57, the point 80 and the contactor 5, to the line conductor 4. Energization 110 of the coil 63 thereupon causes the closing of the reversing contactors 59 and 60, whereupon the motor circuit may be traced from the line conductor 3, through the reversing contactor 59, the armature 1, the contactor 60, the resistor 6, and the line contactor 5 to the line conductor 4. The closing of the contactors 59 and 60 causes the opening of the contactor 67 and the consequent opening of the circuit of the coil 22. A new circuit for this coil is, however, immediately established, in parallel relation to the resistor 6, as above described, between the points 79 and 80. This circuit includes the resistor 86. The armature 32 is thus 125 maintained in actuated position to maintain 130

the bar 40 out of engagement with the armatures 33, 34 and 35 of the relays 25, 26 and 27. If the current is above a previously-selected safe value, the flux of the magnetic field created by the coil 22 will overcome the forces of the springs 51, and the armatures 33, 34 and 35 will remain with the stops 41 in engagement with the pole piece 39 (Fig. 1). As the motor accelerates and the current begins to die down, the magnetic flux set up by the coil 22 becomes weakened. After a time, when the flux has decreased to a predetermined value, the spring 51, attached to the armature 33, will overcome the force exerted by the flux of this field, so that the relay 25, controlled by the armature 33, will be closed. The time when this operation will occur will depend upon the size of the air gap 70 and the tension of the spring 51. The armatures 34 and 35, however, will remain open. The closing of the relay 25 establishes the above-described circuit of the coil 19. The contactor 10 is thereupon closed to short-circuit the section 13 of the resistor 6. The motor then further accelerates, and, by decreasing the voltage across the terminals of the coil 22, the magnetic field in the neighborhood of this coil is further weakened, which permits the closing of the second relay 26, controlled by the armature 34. A circuit is then completed from the line conductor 3, by the conductor 28, through the contact members 16, the coil 20, the relay 26, the point 80 and the contactor 5, to the line conductor 4. The coil 20, thus becoming energized, causes the closing of the contactor 11 and the consequent shunting of the second portion 14 of the resistor 6. After the motor has accelerated further, the magnetic field surrounding the coil 22 is again weakened and the relay 27 is closed, creating a circuit extending from the contact members 16, which, as above described, are connected to the line conductor 3, through the coil 21, the relay 27, the point 80 and the contactor 5, to the line conductor 4, thereby causing the closing of the contactor 12 and the shunting of the third portion 15 of the resistor 6. The whole resistor 6 is then entirely shunted from the armature circuit and the armature 1 is connected directly across the line.

The shunting of the resistor 6 de-energizes the coil 22 which would release the armature 32 and cause the relays 25, 26 and 27 to be reopened, thus resulting in de-energization of the coils 19, 20 and 21 and the consequent reinsertion of the resistor 6 into the armature circuit, except for the coil 23, which becomes energized at the same time with the coil 21, upon the closing of the armature 35 of the relay 27. The circuit of this coil is from the line conductor 3, by the contactor 28, through the contact members

16, the coil 23, the relay 27, the point 80 65 and the contactor 5, to the line conductor 4.

It will be noted that the motor cannot be started until the contact members 55 and 57 have been closed to close the circuit of the coil 63 (or, if operation in the reverse direction be desired, the coil 62). The contact members 55 and 57, moreover, cannot be closed until the armature 32 has been actuated by the coil 22, which, in turn, cannot be energized until the reversing contactors have 70 opened, and the contactors 66 and 67, mechanically connected thereto, have been closed. It is thus impossible to start or to reverse the motor until after the reversing contactors all occupy their inoperative 75 positions. If, then, the controller 7 be moved suddenly from one operative position to the other to effect reversal of the motor, it will be impossible to effect the operation of the motor in the reverse direction, with 80 the relays 25, 26 and 27, and, consequently, the contactors 10, 11 and 12, closed, and, therefore, with the resistor 6 entirely short-circuited. The danger of suddenly throwing the motor across the line without any resistance in circuit with the armature is thus 85 avoided.

The system of Fig. 5 is similar to that of Fig. 4, with the exception that the initial actuation of the armature 32 is effected by 90 the coil 23, instead of by the coil 22. The essential difference is that the coil 22 is permanently connected, at 95 and 80, in parallel circuit with the resistor 6 and is not, as in the system of Fig. 4, at any time connected directly across the line. The coil 23 is initially connected in a circuit extending from the line conductor 3, by the conductor 28, the contact member 9a or the member 18a, as the case may be, the coil 23, the contactors 67 and 66, the point 80 and the contactor 5 to the line conductor 4. Upon the closing of this circuit, the armature 32 is actuated to force the bar 40 out of engagement with the armatures 33, 34 and 35 (Fig. 110 1). When the contactor 67 or the contactor 66 is opened by the coil 63 or by the coil 62 to close the reversing contactors for forward or reverse operation of the motor, the circuit of the coil 23 is broken, but the circuit of the coil 22 is energized, upon the closing of the motor circuit, to maintain the armature 32 in actuated position. When the resistor 6 is entirely short-circuited by the 115 closing of the relays 25, 26 and 27, the coil 22 becomes de-energized but the coil 23 becomes again energized simultaneously with the closing of the relay 27.

The circuits may be traced as follows: upon actuating the controller 7, for example, to the right, a circuit is completed which extends from the line conductor 3, by the conductor 28, the contact members 18a and

the actuating coil 8 to the line conductor 4. The contactor 5 is thereupon closed. The above described circuit of the coil 23 is also closed at 18a, the coil 23 becoming thereby 5 energized to actuate the armature 32. The switches 55 and 57 are also thereupon closed, whereupon a circuit may be traced from the line conductor 3, by the conductor 28, through the contact members 18b, the actuating 10 coil 62, the contact members 55 and 57, the point 80, and the contactor 5, to the line conductor 4. The armature circuit may then be traced from the line conductor 3, by a conductor 28b, through the contactor 61, the 15 armature 1, the contactor 58, the point 70, the resistor 6 and the contactor 5, to the line conductor 4. The circuit of the coil 23 is broken at 66 and the circuit of the coil 22 is energized in shunt to the resistor 6 at 20 the points 79 and 80. When the relay 25 closes, in accordance with the circuit conditions, as described in connection with Fig. 4, a circuit for the actuating coil 19 of the contactor 10 is established from the line conductor 3, by the conductor 28, the contact members 18b, the coil 19, the relay 25, the point 80 and the contactor 5, to the line conductor 4. The contactors 11 and 12 are similarly closed upon the closing of the relays 25 and 27, the closing of the latter relay serving also to close a new circuit for the coil 23, which extends from the line conductor 3, by the conductor 28, through the contact members 18a, the coil 23, a resistor 24a, the relay 27, the point 80 and the contactor 5, to the line conductor 4. Upon the de-energization of the coil 22, therefore, when the resistor 6 becomes entirely short-circuited, the coil 23 becomes energized to 30 maintain the relays closed, and the resistor 6, therefore short-circuited.

It will be noted that, in the system of Fig. 5, before the motor can be reversed, by actuation of the controller 7 from one operative 45 position to the other, the circuit of the coil 23 will be broken to cause the release of the armature 32 (Fig. 1). Assuming the motor to be running as above described, the circuit of the coil 23 will be broken at the contact members 18a. The relays 25, 26 and 27 will thereupon open to break the circuits of the actuating coils 19, 20 and 21 of the contactors 10, 11 and 12, thereby to cause the resistor 6 to be reinserted into the armature 50 circuit before the reversal of the motor. When the controller 7 bridges the contact members 9a, a new circuit will be created for the coil 23, preliminary to the reversal of the motor, and the operation will then 55 proceed as before described, but with the reversing contactors 59 and 60, instead of those indicated at 58 and 61, closed; but before the motor can be started in the reverse direction, the resistor 6 will be in circuit 60 with the armature. The same safeguards

attending the operation of the system of Fig. 4 thus attend also the operation of the system of Fig. 5.

It will be obvious that many changes may be made in the circuits and apparatus above described without departing from the spirit of my invention. For example, my invention is not limited to the use of the relay invented by De Camp, for I may employ relays of ordinary kinds, as discussed in my above-mentioned applications, Serial Nos. 236,937 and 249,344. Or I may modify the De Camp relay, doing away with the contact members 55 and 57 and having their function performed by an additional relay 75 like those numbered at 25, 26 and 27. Other changes will be obvious. I desire, therefore, that my claims be broadly construed, except in so far as limitations may be expressly set forth therein. 85

I claim as my invention:

1. The combination with an electric motor, a resistor in circuit therewith, a switch for closing the circuit of said motor, and a coil for actuating said switch, of a relay mechanism for controlling said resistor and the circuit of said coil, said relay mechanism comprising an actuating coil, and a switch mechanically connected to said first-named switch for controlling the circuit of said 90 relay coil.

2. The combination with an electric motor having a resistor, a pair of reversing switches for said motor, and a coil for controlling said resistor, of switches mechanically connected to said reversing switches for closing the circuit of said coil before the starting of said motor. 100

3. The combination with an electric motor having a resistor, a pair of reversing switches for said motor, a coil in parallel circuit with said resistor for controlling the short-circuiting of said resistor, and a coil for maintaining said resistor short-circuited, of switches mechanically connected to said reversing switches for closing the circuit of one of said coils before the starting of said motor. 105

4. The combination with an electric motor having a resistor, a pair of reversing switches for said motor, each having an actuating coil, and a switch for short-circuiting said resistor, of a switch for closing the circuits of said coils, and a coil for closing said closing switch and for controlling said 110 resistor switches. 115

5. The combination with an electric motor having a resistor, a source of energy for said motor, a pair of reversing switches for said motor, and a coil, of switches mechanically connected to said reversing switches for connecting said coil to said source to start said motor, and means for thereupon connecting said coil in parallel circuit with said resistor to short-circuit said resistor. 125 130

6. The combination with an electric motor having a resistor, a source of energy for said motor, a pair of reversing switches for said motor, a coil in parallel circuit with said resistor for controlling the short-circuiting of said resistor, and a coil for maintaining said resistor short-circuited, of switches mechanically connected to said reversing switches for connecting said maintaining coil to said source to start said motor.

7. In a reversing system for electric motors, the combination with an electric mo-

tor having a resistor, and a pair of reversing switches for said motor, of a coil for controlling said resistor and said switches, and a pair of switches mechanically connected to said reversing switches for preventing the energization of said coil except when said reversing switches occupy inoperative positions.

In testimony whereof, I have hereunto subscribed my name this 30th day of Oct., 1918.

HENRY D. JAMES.
